ATTORNEY

UNITED STATES PATENT OFFICE

GEORGE BRAIN, OF NEW CASTLE, PENNSYLVANIA, ASSIGNOR TO AMERICAN DRESSLER
TUNNEL KILNS, INC., OF NEW YORK, N. Y.; A CORPORATION.

DEVICE FOR SUPPORTING TABLEWARE.

1,333,380.

Specification of Letters Patent.

Patented Mar. 9, 1920.

Application filed June 17, 1919. Serial No. 304,949.

To all whom it may concern:

Be it known that I, GEORGE BRAIN, a subject of the Kingdom of Great Britain, residing at New Castle, county of Lawrence, 5 State of Pennsylvania, have invented certain new and useful Improvements in Devices for Supporting Tableware, of which the following is a specification.

My invention consists in a device for supporting table ware in kilns of the type where the products of combustion are not discharged into the interior of the kiln. In the ordinary type of kiln, where the products of combustion enter the kiln, it is necessary to 10 inclose and support table ware and other articles which are liable to be injured, in saggers. By the use of my invention, saggers are done away with, and the articles are supported in such a manner as to separate them and expose them to the temperature of the kiln.

The accompanying drawings will serve to illustrate my invention, in which:

Figure 1 is an elevation of two units of 25 my improved supporting device.

Fig. 2 is a perspective view of the under side of the upper plate of the supporting device.

Fig. 3 is a plan view of the supporting device and a plate.

Fig. 4 is a vertical section through one of the pillars of the supporting device and separating plug, also showing two of the supporting pins and a portion of a plate in 35 elevation.

In the drawings, 5 indicates the bottom plate of the frame of the supporting device, which is shown as triangular in shape. It may, however, be given any shape. Located 40 in the bottom of the frame plate, are recesses 6, adapted to receive separating plugs 7, which are usually made of clay and which serve to elevate the bottom frame plate above the supporting surface 8, upon which the

supports are carried, as for instance, the 45 bottom of a kiln or the bottom or shelves of a carriage moved through the kiln. Projecting vertically upward from the bottom frame plate are pillars 9. Formed in these pillars are recesses 10, which are shown as 50 inclined from within outward and downward. They may, however, be disposed horizontally. The recesses 10 are shown as equally spaced; they may, however, be unequally spaced. Situated in the recesses are 55 pins 11. These pins are designed to support plates or other table ware, generally indicated at 12. Overlying the pillars 9, is a top plate 13. The pillars 9 may be provided with recesses 14 at the top, and the top plate 60 13 may be provided with projections 15 which enter the recesses 14. In the use of the device, three pins such as 11^a are first introduced in the bottom recesses 10. A plate is then placed over the pins, and then subsequent pins and plates, until the holder is full. If desired, a series of supports may be placed one on top of the other, as indicated in Fig. 1.

Having thus described my invention, I 70 claim:

1. A support for table ware, comprising a bottom frame plate, removable pins in the bottom of the bottom frame plate, pillars projecting upward from the bottom frame 75 plate provided with recesses, and removable pins in said recesses.

2. A support for table ware, comprising a bottom frame plate, removable pins in the bottom of the bottom frame plate, pillars 80 projecting upward from the bottom frame plate provided with recesses, removable pins in said recesses, and a covering plate.

In testimony whereof I affix my signature.
GEORGE BRAIN.
